Specification of Letters Patent.

Patented Dec. 7, 1909.

Application filed July 6, 1905. Serial No. 268,494.

To all whom it may concern:

Be it known that I, Louis M. Potts, a citizen of the United States, residing at Baltimore city and State of Maryland, have 5 invented certain new and useful Improvements in Automatic Telegraphs and the Like, of which the following is a specification.

The principal object of this invention is 10 the transmission of intelligence by automatic telegraphy, though the said invention in some of its aspects is applicable also to the operation of type-casting or type-setting machines, and the rapid production or re- 15 production of printed matter of various kinds.

For the purposes of the present description, I have selected as a specific application 20 of my invention, the case in which it is used as a rapid automatic page printing telegraph, wherein the messages are automatically transmitted in multiple line form and received and automatically printed in the same or substantially the same form. In 25 such a system I have combined the rapid, the multiplex, and the printing telegraphs in one, wherein the valuable features of each are selected and practically all of the objectionable features of each are gotten rid of.

30 In order to more fully describe this form of my invention, reference will be had to the accompanying drawings wherein—

Figure 1 represents one of the telegraph forms prepared for sending; Fig. 2, a diagram of a form of the sending apparatus and electric circuits; Fig. 3, an enlarged fragmentary top plan view of the sending blank and one set of brushes; Fig. 4, a diagram of a form of the receiving apparatus and electric 35 circuits; Fig. 5 is a diagram of a form of receiving apparatus and electric circuits arranged to automatically reproduce or re-prepare a sending form for transmission; Fig. 6, an enlarged detail sectional view of 40 the perforator used with the apparatus shown in Fig. 5; and Figs. 7 to 10 inclusive represent respectively the sending, receiving, combination commutators and type-wheels in development.

50 In the following description I shall take up first the sending form, then the transmission of messages by means of said forms.

The sending form.—The sending form consists of a sheet or page of paper or other suitable material having thereon a plurality 55 of impressions arranged in accordance with a preselected code, and, if desired, a printed or typewritten character corresponding to each code impression or combination of impressions representing such character. 60 These impressions may consist of perforations, embossments or any other forms of impression which will accomplish substantially the same result. The message is impressed on the blank in a series of horizontal 65 lines as in ordinary writing, and when printed characters are used, the code impressions are arranged in a vertical line either directly above or below the printed character represented thereby. In the specific 70 form of my invention herein shown the code impressions are in the form of small perforations 1 (see Fig. 1), and two of such perforations are combined, according to a code now to be described, to form a 75 letter of the alphabet, numeral, or other symbol. The code herein described is substantially that of the Rowland system, described in one form in the Patent No. 713,497, to Henry A. Rowland, granted 80 November 11, 1902, wherein eleven circuits of a keyboard are combined two-and-two to effect a large number of combinations, each of which effects the transmission of a different signal.

85 For the purpose of explaining how the perforations are arranged on the sending form according to this code, let the form (Fig. 1) be divided by a series of imaginary horizontal parallel lines of four groups, indicated by the dotted lines lettered *a*, *b*, *c*, *d*, *e*, *f*, *g*, *h*, *i*, *j* and *k*, and let each of these lines correspond to an electric circuit. Then, as in the Rowland system, by combining these circuits two-and-two, fifty-five combinations may be effected, each of which may be made to transmit a different signal or character, or perform some other function. In the present system these circuits are combined two-and-two by arranging for each character, symbol, or signal, two perforations in a vertical line, and each perforation of a combination in a separate horizontal line. For example, the code arrange- 90 95 100

ment of perforations to produce the letter "A" consists of a perforation on the horizontal line *b* and a perforation located directly thereunder on the horizontal line *f*.
 5 The code arrangement for the letter "J" consists of two perforations located one above the other on the *c* and *i* lines, respectively, and so on. Each vertical line of perforations forming a combination is
 10 spaced a suitable distance horizontally from the next adjacent combination. At the same time that the form is perforated, the character or symbol representing the combination of perforations, may be printed or
 15 typewritten thereon, preferably directly above or beneath the code perforations. In the specimen illustrated in Fig. 1, these printed characters are directly beneath the code perforations. In this way the message may be easily read and mistakes
 20 readily detected before transmission.

Each sending form is provided with a series of auxiliary perforations 2, along one of its edges, preferably opposite the commencement of each line of printed matter.
 25 These perforations, as will hereinafter more fully appear, register with retaining devices on the transmitting apparatus for imparting motion to the form, and act also as a
 30 means for accurately placing the forms in the transmitter each time in the proper position. These sending forms may be prepared in any suitable way, and I do not herein claim any specific mechanism for
 35 accomplishing this.

The telegraph circuits and apparatus.—These are shown in one form in Figs. 2, 3, 4, 5, and 7 to 10, to which reference will now be had, and more particularly first to Figs.
 40 2, 3 and 7. In the present case, the main line current is an alternating current of a frequency of about 100 complete cycles per second, and is lead off from the secondary of a transformer 94, having an intermediate
 45 and two outside terminals. The intermediate terminal is connected to earth, and the outside terminals connected respectively to the tongue contacts 95 and 96 of a main line transmitter 97, so that the current when
 50 sent to line through contact 96 differs 180° in phase from current sent to line through contact 95. This transmitter is of a form of well known polarized transmitting relay having two independent electromagnets 98
 55 and 99 arranged to act on the pivoted tongue 100, which is electrically connected to the metallic side 101 of the main line. The windings of the magnet 98 are connected through a resistance 102 to wire A' leading
 60 to the positive pole of a source of direct current supply. One terminal of the windings of the magnet 99 is connected through a smaller resistance 103 to the positive wire A', and the other terminal to a continuous
 65 metal contact ring 104 of the local automatic

transmitting apparatus. This automatic transmitting apparatus consists, among other parts, of a segmental ring 105 of substantially the same diameter as the ring 104 lying alongside thereof and insulated therefrom, these two rings forming what I shall herein designate the "sending commutator."
 70

In the specific form of apparatus herein shown, the ring 105 consists of one hundred and twelve insulated segments. In each 75 octant of this ring is a group of eleven segments, represented by the shaded segments S', S², S³ and S⁴, and each group of these segments is separated from the next adjacent group by three segments represented by the unshaded segments (see Fig. 7). Such a sending commutator is designed for use with two four-line automatic transmitters for automatically transmitting a maximum of four lines of matter abreast. If a 80 greater number of lines are to be transmitted a greater number of groups of segments would be employed. In the case shown, the segments of one-half of the sending commutator could operate in conjunction with one 85 of such automatic transmitters and those in the other half with the other of such transmitters. Since these local automatic transmitters may be identical, I have shown only the one operating with the segments in the 90 right hand half of the ring 105, Fig. 2, such segments being indicated by the groups S', S², S³ and S⁴ in Fig. 7. The eleven segments of each of these groups are electrically connected respectively to eleven separately 95 insulated contact brushes of each of the four groups of brushes 106, 107, 108 and 109; that is, the eleven brushes in group 106, for example, are connected each to a separate segment of group S'; the brushes in group 106 100 similarly connected to group of S², and so on. In the diagram only two brushes in each group are shown connected to their respective segments.

The brushes of each group 106—109 are 105 spaced apart a distance corresponding to the distance between the horizontal dotted lines *a*, *b*, *c*, *d*, *e*, *f*, *g*, *h*, *i*, *j* and *k* on the sending form, Fig. 1, and all of the brushes are accurately adjusted to have their contact points lie in a straight line, extending longitudinally across the top of a rotatable metallic cylinder 110. In sending, the form 111 is inserted between the brushes and cylinder. Four guide pins 112 on the cylinder 110 are arranged to register with and pass through the four perforations 2 in the sending form, thereby holding it to the cylinder. This arrangement also insures the placing of the form on the cylinder each time in the 115 proper position.

As a means for imparting rotary motion to the cylinder 110, I have shown a ratchet wheel 113 mounted on the end of the cylinder shaft 114 and adapted to be operated 120

by a pawl 115 carried by an arm 116 mounted loosely at one end on the shaft 114 and resting at its other end on a cam 117 carried upon a shaft 118. This shaft 118 carries an arm 119 which drives the sending commutator brushes 120 and 121, the former resting on the ring 104 and the latter on the ring 105. Both of said brushes are, however, electrically connected. The pawl 122 is merely to prevent backward rotation of the cylinder when the pawl 115 moves backward. The commutator brushes are driven preferably at a constant speed by a small electric motor, not shown, and their angular velocity is such that the time consumed in passing over each of the grouped segments is equal to the time of a half of a complete alternation of the line current, so that for each segment swept over by the brushes 121, a semicycle of the alternating current will pass to line. This result may be obtained by driving the alternator which produces the line current by the same motor which drives the sending commutator brushes. The tongue 25 of the transmitter remains, under the influence of the magnet 98, normally against the contact 95, so that the alternating current passes to line normally through this contact. Electrical connection may be established between the cylinder 110 and the negative wire B' in any suitable way or through a brush 123, resting on the shaft 114.

The receiving circuits and apparatus.—The receiving apparatus consists, among other parts, of a main line polar relay 126, having its coils connected in the line as shown. The tongue contacts 127 and 128 of this relay are connected each to a point near an end of a resistance 129 connected across a direct current circuit of preferably 110 volts. From an intermediate point in said resistance is led off a wire 130, to which is tapped a number of branch wires 131. Each of these branch wires connects to one coil terminal of each of the polar relays a', b', c', d', e', f', g', h', i', j' and k', which I shall herein designate "selecting relays". The other coil terminals of the eleven selecting relays a' to k' are connected respectively to eleven consecutive segments of the segmental ring 132, which ring together with the continuous metal contact ring 133, I shall designate the "receiving commutator". The segments of the ring 132 correspond in number, grouping and angular position exactly to the segments of the sending commutator ring 105.

For each group R' to R^s of the receiving commutator segments, there is a bank of selecting relays, and the coil terminals of these relays not connected to the common return 130 are connected respectively to the segments of the receiving commutator just as the brushes 106—109 are connected to the 65 segments of the sending commutator. It

will, therefore, be understood that while I have shown only one bank of selecting relays, there would be eight such banks if all of the eight groups of receiving segments are used, or only four banks with the recording device actually shown. The connections of all of these banks of relays are identical, so it is not necessary to show but one. In the bank of relays shown, two are shown with their coils connected to the receiving 70 commutator as by wires 134 and 135. The other relays are similarly connected to the remaining segments of the group adapted to operate with the bank of relays shown.

The selecting relays a' to k' are so wound 80 and connected that the coils of relays a', c', e', g', i' and k' receive current each time that the main line relay tongue engages contact 127, for example, in such a direction as to send all their tongues against their back 85 stop contacts. Likewise, the coils of the remaining selecting relays, namely, b', d', f', h' and j', receive current in such direction each time that the main line relay tongue engages contact 128, for example, as to send 90 their tongues against their forward contacts also. Normally, therefore, all of the selecting relay contacts remain against their back stop contacts. The tongue of the main line relay is connected as by wire 136 with the 95 contact ring 133.

Electrical connection is established between successive segments of the ring 132, and the ring 133, by brushes 137 and 138. These brushes are driven in accurate synchronism with the brushes of the sending commutator and occupy corresponding angular positions. While synchronous motion of these two sets of brushes is an essential requisite of the system herein shown, 105 the specific method of or means for obtaining this synchronism forms no part of my present invention, since any one of several methods may be employed. I prefer, however, to employ the system of synchronizing 110 forming the subject of my invention set forth in U. S. Patent No. 726,750, granted to the Rowland Telegraphic Company, April 28, 1903.

The receiving commutator and selecting 115 relays coöperate, in the case shown, with four combination commutators, C', C², C³ and C⁴ and with a series of relays to operate recording devices. These combination commutators consist each of two continuous 120 metal contact rings 141 and 142 and between these and insulated therefrom are two insulated segmental rings 143 and 144. In the form shown, these rings 143 and 144 contain each the same number of segments 125 as the sending and receiving commutators respectively, and the segments of the two rings are arranged opposite each other, that is, they do not break joints. In each half of the rings 143 and 144 are forty-one 130

combination segments, represented by the shaded segments in Fig. 9. The combination segments in the left hand half of the commutators C', C², C³ and C⁴, Fig. 4, co-operate with the receiving segments R' to R⁴ and operate one recording device, the one shown, and the combination segments in the opposite half of said commutators co-operate with the receiving segments R⁵ to R⁸ to operate the other recording device. That is to say, the set commutators are so mounted and adjusted that the combination segments for operating one recording device occupy angular positions diametrically opposite the groups of receiving segments with which they co-operate. The object of this arrangement will more fully hereinafter appear.

Each pair of combination segments in the left hand half of the commutator C⁴ (lower half of Fig. 9) is connected to a different combination of two wires leading respectively from the eleven forward contacts of the selecting relays a' to k'. By a "pair" of combination segments is meant a segment with one ring (143) and one occupying a corresponding angular position in the other ring (144) thereof. Calling the eleven wires leading from the contacts of the eleven selecting relays a, b, c, d, e, f, g, h, i, j and k, it will be readily seen that wires a and c may be connected respectively to one pair of combination segments; wires a and d to another pair of such segments; wires a and e to another pair; wires a and f to another pair; and so on until the forty-one pairs of segments have been connected to a different combination of the eleven wires. This combination arrangement is fully described in the patent to Henry A. Rowland, No. 713,497, hereinbefore referred to. In the drawing, Fig. 4, I have shown one pair of the combination contacts of the commutator C⁴ connected by wires 139 and 140 to the forward contacts of two of the selecting relays.

Each combination commutator is provided with four electrically connected brushes 145, 146 and 147, 148 which rest respectively upon the rings 141, 143 and 144, 142. These brushes may be driven in any suitable manner from a shaft 149 which rotates in synchronism with the receiving and sending commutator brushes. In the apparatus shown, all of these brushes are mounted in a straight line and occupy angular positions corresponding to the brushes 137 and 138 of the receiving commutator.

The recording devices, one only of which is shown, consist each, among other parts, of four type-wheels 150 mounted on the shaft 149 or driven in synchronism therewith in any suitable manner. These type-wheels are so mounted that each character on the periphery thereof will correspond angularly with a pair of segments in the rings 143, 144 constituting the combination

of segments to print that character (see Figs. 9 and 10).

Beneath the type-wheels is a paper carrying cylinder 151 having annular recesses 152, one directly beneath each type-wheel. 70 Into these recesses extend four metal printing levers 153, pivoted as at 154, and having each at one end a platen 155 arranged to strike upward and send the paper 156 against the type-wheel. These printing levers are operated by four electro-magnets 157 located beneath their ends opposite the platens. The cylinder 151 is carried on a shaft 158 to which it is made fast, and upon this shaft is a ratchet wheel 159 operated 80 by a pawl 160 carried by an arm 161 pivoted at one end on the shaft 158, and engaging near its other end a cam 162 carried by the type-wheel shaft. Backward motion of the ratchet is prevented by the auxiliary 85 pawl 163. This ratchet and pawl cam operated mechanism constitute a means for imparting a step-by-step motion to the paper upon which the characters are being printed, such motion corresponding to the step- 90 by-step motion of the transmitting cylinder 110.

The printing magnets are operated in four relay circuits, each of which is controlled by one of the four relays 164. Each of these relays has a magnet coil connected in series between the positive pole of a source of direct current and a ring 141 of one of the combination commutators, the other contact ring of each of said combination commutators being connected to the negative pole of said source of current. The other magnet coils of the relays 164 are connected in series between the positive pole of said source of current and stationary contacts 100 165 arranged to be engaged by spring contacts 166 on the ends of the respective printing levers, which are in turn connected to the negative pole of said source of direct current.

The operation is as follows: A sending form, such as shown in Fig. 1, is prepared in any desired way, and placed upon the cylinder 110, as shown in Fig. 2. Each revolution of the cam 117 causes the pawl 115 to step the ratchet 113 around a certain distance, and this imparts a step-by-step rotary motion to the cylinder 110. After a few of such steps, the first line of perforations on the form extending longitudinally of said cylinder will be brought beneath the brushes 106-109. By referring to Fig. 1, it will be seen that this first line of perforations extending vertically of the sheet includes a perforation on the c line 115 and one on the i line of the top group; no perforations in the second group; a perforation on the e line and one on the h line in the third group; and one on the a line and one on the g line of the fourth group. 120

Therefore the brushes of the group 106 which are in line with the *c* and *i* perforations will make contact therethrough with the metal cylinder 110, and likewise with 5 respect to the brushes of the other groups which lie in line with the first line of perforations.

When the brushes 121 reach the first segment in their path, connected to a brush 10 which engages a perforation in the sending form, this completes a circuit, which, assuming that the segment engaged is the one connected to wire 124, may be traced as follows: from the positive wire A' through resistance 103, coil of transmitter magnet 99, contact ring 104, brushes 120 and 121, segment of ring 105, wire 124, brush of group 15 106 engaging the cylinder 110 through the first perforation on the *c* line in the top group (Fig. 1), through cylinder 110, brush 123, back to the negative wire B'. The circuit thus completed energizes magnet 99 of the transmitter, and causes it to draw the tongue 100 over against the contact 96. The 20 tongue, however, remains there only so long as the brushes 121 are passing over the segment connected to the wire 124. The effect of this is to change the line connections of the transformer 94 and send to line a semi- 25 cycle of opposite sign to the normal. A local circuit is also completed through the coils of transmitter magnet 99 when the brushes 121 reach the segment connected to wire 125 causing a second reversal of the 30 line current. Likewise, when the brushes 121 reach the other segments connected to the brushes of the groups 106-109 which engage the cylinder 110 through perforations in the sending form, two line impulses 35 will be reversed for each pair of such segments. The effect of these reversed semicycles is to cause the tongue of the main line receiving relay (see Fig. 4) to remain, each time its coils are traversed by such 40 reversed semicycles, against the opposite contact to that to which it would have been sent had no reversal taken place, and the effect of this is to cause two of the selecting relays to receive current in a direction 45 opposite to the normal, and this will cause them to send their tongues against their forward contacts.

Let it be assumed that the first reversed line semicycle causes the tongue to the main 55 line receiving relay to stick against contact 128 instead of going over to contact 127, as it would have done normally, and let it further assumed that at that instant the receiving commutator brushes are in engagement with the segment connected to wire 134. A circuit will then be completed which may be traced as follows: from the positive side of the resistance 129, through contact 127 and tongue of the main line receiving 60 relay 126, wire 136, ring 133, receiving com-

mutator brushes, the segment of the ring 132 thereunder, wire 134, coils of selecting relay *c'*, wire 131, wire 130, back to the intermediate point of resistance 129. The current passing thus will cause the tongue of the 70 selecting relay *c'* to be sent against its forward contact for the reason that the main line relay tongue is against contact 128, causing current to traverse the coils of selecting relay *c'* in a direction opposite to the 75 normal. In a similar manner current is sent through the coils of the selecting relay *i'* when the second reversed semicycle causes the tongue of the main line relay 126 to stick against the opposite contact to which 80 it would have been sent by a normal current. The tongues of selecting relays *c'* and *i'* having been sent over against their forward contacts, a circuit is completed through one of the coils of the relay 164 as soon as 85 the brushes 146 and 147 of the combination commutator arrive upon the combination of segments connected to the wires 139 and 140 connected to the forward contacts of the selecting relays operated. Assuming that the 90 brushes 146 and 147 have reached said segments, the relay operating circuit may be traced as follows: from the positive wire A² leading from a source of direct current supply, to wire 167, left hand coil of one of the 95 relays 164, wire 168, contact ring 141, brushes 145 and 146, segment of ring 143, wire 140, forward contact of selecting relay *c'*, through the tongue of said relay to the tongue of relay *i'* (all of the tongues of 100 said selecting relays being electrically connected) forward contact of relay *i'*, wire 139, segment of ring 144 connected to said wire, brushes 147 and 148, ring 142, wire 169 to the negative wire B² of the source of 105 current supply. This circuit causes current to flow through the left hand coil of relay 164, and this sends the tongue 170 of said relay against contact 171, which completes a circuit through the printing magnet 157, 110 which circuit may be traced as follows: from the positive wire A², through wire 172, winding of print magnet 157, wire 173, relay contact 171, tongue 170, wire 174, back to the negative wire B². Current passing 115 through this last named circuit energizes the print magnet 157, and causes it to attract one end of the print lever 153, sending the platen thereof against the paper in front of the character on the type-wheel which corresponds to the combination of segments of the combination commutator connected to the wires 139 and 140. This operation prints the letter "J", the first letter of the first word on the sending form, Fig. 1.

When the print magnet attracts the end of the print lever, the contact 166 is brought into engagement with the stationary contact 165, and this completes a restoring circuit which may be traced from the positive wire 130

A² through the right hand magnet coil of the relay 164, wire 175, contacts 165 and 166, print lever 153, and through wire 176 to the negative wire B². The completion of this circuit causes the right hand magnet of relay 164 to draw its tongue against its back stop to its initial position, breaking the circuit through the print magnet. When the transmitter brushes 121 reach the next group of segments, those in Fig. 2 connected to the group of brushes 107, no transmission is effected, for, as will be observed from the sending form, there will be no code perforations at that instant beneath brushes 107. 10
 It will be remembered that we are still considering the case where the line of brushes 106-109 are on the first vertical line of perforations on the left, Fig. 1. When the brushes 121 reach the third and fourth 15 groups of transmitting commutator segments, namely, those connected to brushes 108 and 109, (groups S³ and S⁴, Fig. 7) the letters "I" and "W" will be transmitted. These letters will be printed respectively by 20 the two print levers on the left (Fig. 4), while the print lever next to the lever 153 will remain at rest, for, as explained, there are no code perforations at this time beneath brushes 107. 25
 After the brushes 121 have passed over the four groups of commutator segments connected to the brushes 106-109, the cam 117 operating the arm 116 causes the ratchet and pawl mechanism to step the cylinder 30 around a predetermined distance, that is, the distance of one row of perforations extending longitudinally of said cylinder to the next, whereby the brushes of the groups 106-109 are brought into line with the next 35 row of perforations, and when the brushes 121 come in contact with the segments connected to the brushes contacting with the cylinder through this next line of perforations, the main line transmitter will again 40 be operated as above described to reverse an impulse of the line current for each segment so connected. This will send over the line the next series of signals. After this, the perforated form is again spaced up to 45 the next perforations as described, and so on until all of the perforations have been brought beneath their respective brushes. 50

After the proper printing levers have been operated to print a line of characters abreast, such as the first row or line, "J", "I", and "W" (Fig. 1), the paper 156 is spaced up by the cam 162 acting on the arm 161, which in turn acts through the ratchet and pawl mechanism to impart a limited rotary motion to the cylinder 151. The paper is then ready to receive the next transverse line of characters, after which the cylinder 151 is again stepped around, and this process is carried on until all of the message is printed 60 on the sheet or page 156. 65

If the code perforations arrive simultaneously beneath the several groups of brushes 106-109 representing like characters, these characters will all be printed simultaneously, one on each line. This is so 70 for the reason that combinations of segments representing like characters in each half of the several combination commutators all occupy corresponding angular positions. Therefore, the combination commutator 75 brushes will arrive upon like combinations of segments simultaneously and this will cause all of the print magnets and levers to act simultaneously to print like characters. 80
 This novel method of printing, which consists in printing a plurality of lines of matter abreast, eliminates entirely the necessity of stepping the paper up from line to line. This not only effects a great saving in time by the elimination of an entire step in the 85 pivotal practiced methods of printing, but also gets rid of all of the mechanism necessary to effect such a step. Moreover, by operating two printers, one with each half of the four combination commutators and duplexing the line as shown in the patent to 90 Henry A. Rowland, hereinbefore referred to, or otherwise, the line may be worked to its fullest capacity at all times. 95

The automatic reproduction of sending forms.—An arrangement of circuits and apparatus for accomplishing this is shown in Figs. 5 and 6. In carrying out this feature of my invention, I add to the printer already described, an automatic perforating 100 device consisting, among other parts, of two stationary punch bars 177 and 178 separated by a sufficient space to allow the paper or form to pass between them as shown. In the upper bar 177 are a series of groups of 105 perforating pins 179 normally held up by the springs 180. There are eleven of these pins in each group and one group is located in front of each type-wheel of the printer. For each of these pins there is a 110 separate lever and these levers rest respectively upon the tops of the several pins. In the drawings I have shown two of these as the levers 181 and 182. These levers are arranged for actuation by separate magnets 115 183, 184 and carry, at their outer ends, contacts 185, 186 which are arranged to engage, at the proper time, stationary contacts 187 and 188. In each perforator lever operating 120 magnet there is a separate relay, to the forward contact of each of which the positive coil terminal of each of the said lever operating magnets connects. In the diagram I have shown two of these relays as the relays c², i². These relays have independently 125 wound magnets, one of which acts as an actuating magnet and the other as a restoring magnet. The actuating magnet coils 189, 190 of these relays are so wound that current passing through them normally sends their 130

tongues against their back stop contacts. The actuating magnet coils 189 and 190 of these relays are connected in multiple respectively with the printer coil terminals of the several 5 selecting relays c' — i' , while the restoring coils 191 and 192 are connected respectively to the stationary contacts 188 and 187; and to a wire 193 leading to the positive terminal of a source of direct current. The 10 terminals of the magnets 183, 184 not connected to the contacts of relays c^2 , i^2 are connected to a common wire 194 which leads to the forward tongue contact 195 of a relay 196. This relay 196 has two independent 15 windings, one on the magnet 197 for actuating purposes and the one on magnet 198 for restoring purposes. The windings of these magnets, as well as the tongue of the relay, connect to a common return wire 199 which leads to the negative pole of a source of direct current. One terminal of the actuating magnet 197 is connected to a segment 200 in the combination commutator C' , while one terminal of the restoring magnet 20 25 198 is connected to a segment 201 of the same combination commutator, but lying in the opposite half of said commutator from the segment 200. These segments are entirely independent of the combination segments.

The operation of the automatic perforating arrangement is as follows: Let it be assumed that, owing to a reversal of two line current semicycles from the normal, the 30 main line relay causes current to be sent through the right coils of selecting relays c' and i' in an opposite direction to the normal when the brush 137 arrives upon the segments connected to wires 134 and 135, as was 35 described in connection with the operation of printing. When the brush 137 arrives upon the segment connected to wire 134, current in an opposite direction to the normal will also be sent through the coils of 40 actuating magnet 189 of relay C^2 . This will cause the tongue of that relay to be sent against its forward contact, and in doing so will complete a circuit from the positive pole of local current supply through wire 45 199, tongue of relay 196, contact 195, wire 194, coil of magnet 184, forward contact and tongue of relay C^2 back to the negative pole of current supply. The magnet 184 will, therefore, become energized and attract the 50 one end of lever 182, and causing the other end thereof to send the perforating pin thereunder through the paper. This operation also sends the contact 186 into engagement with the stationary contact 188, and 55 this completes a restoring circuit which may be traced as follows: From the positive pole of the local current supply by wire 193 to the coil of the restoring magnet 191 of relay C^2 , thence to contacts 188 and 186, lever 60 65 182 back to the negative pole. This causes

relay C^2 to break the circuit through the coils of magnet 184, when the lever 182 will return to its normal position.

Before the brushes of the combination commutator C' reached the position shown, 70 they passed over segment 200 and in doing so completed a circuit from the positive pole of the local current source through the coil 197 of relay 196 and this caused its tongue to be sent against the contact 195. When 75 the brushes of the commutator C' arrive upon segment 201, a circuit is completed through the coil 198 of relay 196 and this restores the tongue of said relay to its normal position against its back stop contact. By 80 a similar sequence of operations, the lever 181 is operated by the magnet 183 when the brush 137 arrives upon the segment connected to the wire 135. In this latter case, relay i^2 acts instead of relay C^2 . For each character transmitted over the line, therefore, a 85 separate combination of pins may be made to automatically impress on the form a different combination of perforations, by which means I am enabled to automatically 90 prepare the sending forms. One of these automatic perforators may be used with each printer or without the printers.

Having now described a form of my invention and the manner in which it is operated, I do not desire to be understood as limiting myself to such form, as there are many ways of carrying out the principles of my invention without departing from the spirit of the same.

What I claim is my invention is:—

1. The combination with a prepared sheet, having thereon code impressions arranged in a series of groups of transverse lines, and in code formation in lines passing substantially at right angles to the direction of the said groups of lines, of automatic transmitting means controlled by said sheet, and automatic means to record in multiple lines abreast the intelligence contained in said groups of lines of code impressions.

2. The combination with a prepared sheet, having thereon code impressions arranged in a series of groups of transverse lines and in code formation in lines passing substantially at right angles to the direction of the said groups of lines, of a series of groups of electrical contacts, one group for each group of transverse lines of impressions and arranged to impinge on said sheet; means to effect relative movement between said sheet and contacts in the direction of the transverse lines of code impressions to bring the respective lines of said impressions into engagement with the group contacts abreast; a series of circuits in which said contacts are connected; a main circuit, and means cooperating with said sheet, contacts and plurality of circuits to impress the elements of the code upon said main circuit.

3. The combination with a plurality of groups of electrical contacts, a plurality of groups of normally incomplete local circuits in which said contacts are connected, a main circuit, a prepared controlling sheet having thereon code impressions arranged in multiple lines in groups, means to bring said groups of lines of code impressions abreast into operative relation with the respective groups of said contacts to alter the electrical condition of the circuits in which said contacts are connected, and means coöperating with said controlling sheet to impress the elements of said code on said main line.
4. The combination with a telegraph line, of a main line transmitter connected therein, a plurality of groups of electric circuits for operating said transmitter; a progressive contact maker arranged to connect said transmitter in said circuits successively, and a primary controlling device consisting of a prepared sheet having code impressions thereon arranged in a series of groups of transverse lines, each group of lines of impressions corresponding to a line of matter to be transmitted and each adapted to control a separate group of said circuits.
5. The combination with a telegraph line, of a main line transmitter connected therein, a plurality of groups of electric circuits for operating said transmitters; a progressive contact maker arranged to connect said transmitter in said circuits successively, and a primary controlling device consisting of a prepared sheet having code impressions thereon arranged in a series of groups of transverse lines, each group of lines of impressions corresponding to a line of matter to be transmitted and each adapted to control a separate group of said circuits, and means to automatically print in a plurality of lines abreast, the matter represented by said series of groups of lines of code impressions.
6. The combination with a telegraph line of a main line receiving relay connected therein, a plurality of selecting relays, a plurality of circuits in which the coils of said selecting relays are connected, a progressive contact device coöperating with said main line relay and said circuits to operate said selecting relays, a plurality of circuits in which said selecting relay tongues and contacts are connected, a printer having means to print a plurality of lines of matter abreast, means to combine the circuits in which the selecting relay contacts are connected in accordance with a prearranged code, and means coöperating with said circuit combining means to operate said printer.
7. The combination with means for recording intelligence in multiple line page form, of automatic means to operate said recording means, said automatic means including a primary controlling device consisting of a prepared sheet having code impressions thereon arranged in multiple line page form, said recording means automatically reproducing said code impressions.
8. The combination with a prepared sheet, having thereon code impressions arranged in a series of groups of transverse lines and in code formation in lines passing transverse to the direction of said groups of lines, of automatic means controlled by said sheet to prepare similar sheets.
9. The combination with a prepared sheet, having thereon code impressions arranged in a series of groups of transverse lines, and in code formation in lines passing transverse to the direction of the said groups of lines, of automatic transmitting means controlled by said sheet, and automatic means to print in multiple line page form the intelligence contained in said groups of lines of code impressions and to reproduce said code impressions, both in the same body.
10. The combination with a telegraph line, of an automatic transmitter, a controlling device for said transmitter consisting of a prepared sheet having code impressions arranged thereon in a series of transverse substantially parallel lines in which the intelligence reads from the end of one line to the commencement of the next succeeding line, means controlled by said automatic transmitter to automatically impress corresponding code impressions upon other sheets.
11. Means for the transmission of intelligence, comprising recording mechanism to print the intelligence in multiple-line form, automatic transmitting mechanism to operate said recording mechanism, and a prepared sheet having thereon code impressions arranged in multiple line form to correspond in sequence both as to characters in a line and lines of characters to the characters represented thereby in the printed matter of the recorder, to control the said automatic transmitter in the operation of said recorder.
12. Means for the transmission of intelligence, comprising recording mechanism to print the intelligence in multiple-line page form, transmitting mechanism to operate said recording mechanism comprising an automatic telegraph transmitter, and a prepared sheet in page form having thereon code impressions arranged in a series of lines to correspond in sequence, both as to characters in a line and lines of characters, to the characters represented thereby in the printed page of the recorder, to control the said automatic transmitter in the operation of the recorder.
13. The combination with a plurality of type-wheels, a plurality of platens, one for each of said type-wheels, a plurality of magnets for operating said platens, relays to

control the operation of said magnets, a plurality of rotary circuit-combining devices, and a plurality of selecting relays co-operating as described to operate the relays which control the platen magnets. 5

14. The combination with a plurality of type wheels, a plurality of platens, one for each of said type-wheels, a plurality of magnets for operating said platens, relays to control the operation of said magnets, a plurality of rotary circuit-combining devices, a plurality of selecting relays co-operating as described to operate the relays which control the platen magnets, a telegraph line, a main line relay operated by current passing over said line, a plurality of local circuits for operating said selecting relays, and a sunflower device for co-operating with said main line relay to control said local circuits. 15

15. In combination, a page type-printing telegraph receiver, an automatic page-controlled telegraphic code transmitter, operative connection between the two, including a telegraph line and a source of signaling electric current, the said receiver recording in printed letter characters the code intelligence transmitted over said line. 25

16. The combination with a page type-printing machine, of an automatic transmitter operatively connected to said machine, said transmitter comprising a controlling device consisting of a prepared sheet in page form having thereon code impressions arranged in transverse lines, the intelligence reading from the end of one of said lines to the commencement of the next succeeding line, the said code impressions controlling the receiver to cause the same to print in typographical characters the code intelligence transmitted. 40

17. The combination with a telegraph line and a source of main line signaling current connected thereto, of means acting directly on said main line to alter the electrical condition thereof to form the signals, automatic page-controlled code transmitting mechanism controlling said means, a page type-printing machine and means operable by the main line signaling current to control the operation of said page-printing machine. 50

18. The combination with a prepared sheet, having thereon code impressions arranged in a series of groups of transverse lines and in code formation in each of said transverse groups in lines passing substantially at right angles to the direction of the said groups of lines, of a series of electrical contacts arranged to impinge on said sheet, means to effect relative movement between said sheet and contacts to bring the respective lines of impressions into engagement with said contacts, a series of circuits in which said contacts are connected, a main

line circuit, and means co-operating with 65 said sheet, contacts and plurality of circuits to impress the elements of the code upon said main circuit.

19. The combination with a prepared sheet, having thereon code impressions arranged in a series of groups of transverse lines and in code formation in each of said transverse groups in lines passing substantially at right angles to the direction of the said groups of lines, of a series of electrical 75 contacts arranged to impinge on said sheet, means to effect relative movement between said sheet and contacts to bring the respective lines of impressions into engagement with said contacts, a series of circuits in 80 which said contacts are connected, a main line circuit, means co-operating with said sheet, contacts and plurality of circuits to impress the elements of the code upon said main circuit, and a page type-printing telegraph receiver operatively connected to said main line circuit and controllable by the code elements impressed on said circuit to record in letter form the intelligence transmitted in code form. 85

20. In a telegraph, the combination with a prepared sheet having thereon apparatus-controlling code impressions representing the intelligence to be transmitted, the code characters formed by said impressions following each other in word and line to line form as in ordinary printing, a plurality of electrical contacts, means co-operating with the said sheet to control said contacts, a series of local circuits in which said contacts 90 are connected, a main line circuit, means co-operating with said sheet, contacts and circuits to impress the signals on said main line, and a page type printing machine operated by the signals thus impressed on said 100 line and adapted to record the same. 105

21. The combination with a prepared controlling form comprising a fillet having thereon apparatus-controlling code impressions and the printed characters which said code impressions represent, an automatic telegraph transmitter controlled by said fillet, a telegraph line on which the signals are impressed by said automatic transmitter, and a recorder operatively connected to said line and adapted to be controlled by said automatic transmitter to record the intelligence sent over said line from said transmitter both in typographical printed characters and code impressions on the same impression receiving body, the said body itself constituting a controlling device for automatic transmission. 110

22. The combination with automatic telegraphic transmitting apparatus, of means to control said apparatus, said means comprising a web or fillet having the intelligence to be transmitted arranged thereon in code 125

perforations, a telegraph line on which the signals are impressed, and recording mechanism operatively connected to said line and comprising mechanism to record the said intelligence simultaneously both in typographical characters and apparatus controlling code perforations on the same impression receiving body, the operation of said

recording mechanism being controlled by the code perforations of said web or fillet. 10

In testimony whereof I affix my signature in presence of two witnesses.
